UTENSIL HANDLE

Stephen A. Platt, Decatur, Ill., assignor to U. S.
Manufacturing Corporation, Decatur, Ill., a cor-
poration of Illinois

Application June 8, 1938, Serial No. 212,421

1 Claim. (Cl. 140—71)

This invention relates to handle constructions and method of making the same. These handle constructions are particularly adapted for uses in connection with implements and utensils which require a substantial handle length. Such handles are also strong in construction and will have a long life and also lend themselves readily to the use of the proper material where resiliency is a desirable factor or feature of the handles 10 to be used.

The principal object of this invention is the provision of handles constructed of wire or rod or other suitable material in which the "feel" of a round wood handle or grip is imparted to the 15 user thereof when gripped.

Another object of this invention is the provision of such handles which are simple and strong in construction, attractive in appearance, and which may be manufactured cheaply in 20 quantity production.

To the accomplishment of the foregoing and such other objects as may hereinafter appear, this invention consists in the method of and means of construction, combination and arrangement of parts hereinafter described and then sought to be defined in the appended claim, reference being had to the accompanying drawing forming part hereof and which shows, merely for the purpose of illustrative disclosure, a preferred 30 embodiment of my invention, it being expressly understood, however, that various changes may be made in practice within the scope of the claim without digressing from my inventive idea.

In the drawing:

35 Fig. 1 represents a side elevation of a fly swatter showing one form of handle constructed to embody my invention.

Fig. 2 is a perspective view of the grip end of the handle in the process of construction.

40 Fig. 3 is a perspective view of the completed grip end of the handle of Fig. 2.

Fig. 4 is a rear end view of the grip end of the handle of the preceding figures, and

Fig. 5 is a perspective view of a somewhat modified form of construction of the grip end of the handle.

Referring first to the construction illustrated in Fig. 1 of the drawing, the numeral 1 designates the body or flap of a standard fly swatter. This 50 body or flap 1 is substantially rectangular in shape with its lower corner portions 2 folded along lines 3 which converge to a point at the center or middle of the lower edge of the rectangular body. The folding of these parts forms a 55 triangular pocket which is adapted to receive a

similarly-shaped element or member which is formed on the end of the handle element.

This handle element is designated generally by the reference character 4 and is composed of suitable wire or rod or other material which has 5 sufficient strength to provide as long a handle element as may be desired. This handle element is formed by taking a single length of wire or rod and first bending it at substantially the middle of its length to form the elongated open gripping loop 5 constituting a part of the handle grip.

This loop, as illustrated, has the rounded rear end 6, and two suitably spaced parallelly extending legs 7 and the converging portions 8, which latter are twisted together at their junction 9 to complete the loop 5. The wire or rod extends from the twisted portion 9 as a pair of closely spaced parallel members 10 for a suitable distance forming the handle portion 11. The members are twisted together again at the upper 20

end 12 of the handle portion and then bend outwardly away from each other to form the legs 13 and 14 of a triangle, the said legs having substantially the same angular direction as the lines of bend 3 of the flap 1. Thereafter the free ends 25 of the legs 13 and 14 are bent in opposite directions and toward each other to form the base members 15 and 16 of a triangular loop with the said legs 13 and 14. As illustrated, the length of base members 15 and 16 is short of the full 30

length of the base of the said loop but may, if desired, be so admeasured as to abut each other, end to end, to form a complete triangular loop. 35

As previously stated, in either case, the partial or complete triangular loop forms a fly swatter or utensil mounting means. It is of substantially the same dimensions as the triangular pocket formed in the lower part of the fly swatter body 1, and the diverging legs 13 and 14 of the loop extend parallel to the lines 3 on which the lower 40 corner portions of the fly swatter body are folded so as to afford a good fit and secure anchorage when the customary securing means in the form of staples, stitching and the like is used. A handle thus far completed may be designated as a 45

"flat" handle.

It is desirable to give the feel of a substantially round wood handle or grip to the user of a device of this character. To this end, I provide an auxiliary gripping loop 17 shaped similarly as 50 the loop 5 and arranged in a plane at 90° with the plane of the loop 5. This auxiliary loop 17 has the rounded rear end 18, the spaced parallel legs 19 and the converging portions 20 whose free ends are suitably attached to the handle ele- 55

ment adjacent the twisted portion 9 of the handle element as by welding or soldering at 21 or in any other suitable manner. The four wire grip thus formed has legs 7 and 19 spaced ninety degrees apart and when gripped by the user imparts substantially the feel of a round wooden or other solid handle. Additional auxiliary loops may be used if desired.

The manner of forming and applying the auxiliary loop 17 to the handle may be as follows:

The flat loop 5 is suitably supported in a horizontal plane adjacent a vertically held predetermined length of wire or rod 17¹ at the mid-point of the latter. Horizontally exerted pressure is then applied to wire or rod 17¹ forcing it against the curved rear end 6 of the said loop 5. This pressure bends the said curved rear end in slightly as at 6¹ and crimps the wire 17¹ at 18¹ around the wire or rod of the loop 5 at the said inward bend 6¹.

Thereafter, the oppositely-extending portions of the wire 17¹ about the crimped portion 18¹ are whipped or bent to the shape of the completed loop 17, and their free ends welded or soldered or otherwise fixed to the handle at the twisted portion 9 or at any other suitable location. The bend 6¹ and crimping 18¹ eliminate the necessity of welding or soldering the rounded portions 6 and 18 of the loops 5 and 17 to each other because the dimensions of loop 17 is such that when its free ends are attached to the twisted portion 9, as described, the said crimping 18¹ and the bend 6¹ prevent movement of the curved ends 6 and 18 relative to each other.

In the modification of Fig. 5 crimping and bending have been eliminated and the auxiliary loop 22, otherwise identical with auxiliary loop 17, attached to the loop 5 by welding or soldering the cross junction 23 of the two loops to each other and then bending the wire of the loop 22 into shape and welding, soldering or otherwise attach-

ing its free ends 22¹ to the twisted portion 9 of the handle element.

It is seen that in both forms the handle is composed of but two pieces of wire or rod. The respective elements are very readily made in the factory and their formation merely involves the bending of a required length of material into the form of the "flat" handle and the bending of the auxiliary loops 7 or 22 and attaching of one or more of the latter to the gripping loop 5 of the "flat" handle by welding or otherwise to form the four or more wire gripping portion. This results in the formation of a handle having the special characteristic of imparting the "feel" of a full round wooden handle to the user and while especially designed for implements such as fly swatters or the like, may be used in connection with various forms of implements and utensils.

The constructions described illustrate practical embodiments of my invention. Others are contemplated. For example, the loops 7 and 17 may have other suitable shapes besides those illustrated. It is to be understood, therefore, that I do not restrict myself to the exact methods and means disclosed and that various changes in method, construction, shape and arrangement of parts are to be considered within the scope of my invention as defined in the appended claim.

What I claim is:

In a handle for a fly swatter, utensil and the like having a gripping loop at one end thereof, said gripping loop being provided with an inward bend, an auxiliary gripping loop mounted adjacent said first-named gripping loop at right angles to the plane of the latter, said auxiliary gripping loop having a crimp therein adjacent said inward bend of said first-named loop and being permanently attached to said handle element.

STEPHEN A. PLATT.
